UNITED STATES PATENT OFFICE.

JOHN MEIKLE, OF CHICAGO, ILLINOIS, ASSIGNOR TO VAPORATOR MFG. CO., OF CHICAGO, ILLINOIS, A CORPORATION OF ILLINOIS.

DESIGN FOR A RADIATOR COVER OR SIMILAR ARTICLE.

Application filed August 2, 1926. Serial No. 18,565. Term of patent 7 years.

To all whom it may concern:

Be it known that I, JOHN MEIKLE, a citizen of the United States, and a resident of the city of Chicago, in the county of Cook and State of Illinois, have invented a new, original, and ornamental Design for a Radiator Cover or Similar Article, of which the following is the specification, reference being had to the accompanying drawings, forming a part thereof.

On the drawings:

cover illustrating the design embodying features of the present invention, the ornamentation of the perforated panel and border being only partially illustrated, it being understood that said ornamentation is applied to the entire panel and border.

I claim:

The ornamental design for a radiator cover or similar article, as shown.

JOHN MEIKLE.
